United States Patent Office

Des. 186,748
Patented Nov. 24, 1959

186,748

DISPLAY STAND FOR GREETING CARDS OR THE LIKE

Alton H. Crone, Westwood, Mass., assignor to Colour-picture Publishers, Inc., Boston, Mass., a corporation of Massachusetts

Application January 8, 1958, Serial No. 49,173

Term of patent 14 years

(Cl. D80—9)

FIG. 2

FIG. 1

Figure 1 is a perspective view of a display stand for greeting cards or the like embodying my new design.

Fig. 2 is a top plan view thereof;

Fig. 3 is a top perspective view of the second component under the top in Fig. 1; and

Fig. 4 is a fragmentary front elevational view of the lower portions of Fig. 1.

I claim:

The ornamental design for a display stand for greeting cards or the like, as shown.
